[57] CLAIM

The ornamental design for a specimen collector for a
commode or similar article, substantially as shown and
described.

DESCRIPTION

FIG. 1 is a perspective view of the specimen collector
for a commode in position, the commode shown in
dotted lines for illustrative purposes only;
FIG. 2 is a top plan view of the collector;
FIG. 3 is a front elevational view of the collector;
FIG. 4 is a side view of the collector, it being under-
stood that the opposite side appears as the mirror image
of this view;
FIG. 5 is a rear view of the collector; and
FIG. 6 is a bottom plan view of the collector.
